United States Patent Office.

MATTHEW EASTERBROOK, JR., OF GENEVA, NEW YORK.

Letters Patent No. 65,732, dated June 11, 1867.

IMPROVEMENT IN HARVESTERS.

The Schedule referred to in these Letters Patent and making part of the same.

TO ALL WHOM IT MAY CONCERN:

Be it known that I, MATTHEW EASTERBROOK, of Geneva, in the county of Ontario, and State of New York, have invented certain new and useful improvements in the manner of producing the "Fast and Slow Speed for the Cutters of Harvesters;" and I do hereby declare that the following is a full, clear, and exact description thereof, reference being had to the accompanying drawings, making part of this specification, in which—

Figure 1 is a top view of my invention.

Figure 2 is an inside elevation, showing a section of the working parts, taken in the plane indicated by the red line *o* in fig. 1.

Like letters indicate corresponding parts in both figures.

This invention consists in arranging two loose pinions upon the crank-shaft of harvesters, so as to gear into two separate sets of teeth—each set having a different radius—upon the face of a bevel-wheel on the counter-shaft, and providing one or more suitable clutches feathered to the crank-shaft and operated by a hand-lever, whereby either pinion may be locked to the crank-shaft, and its speed be increased or decreased, as desired.

To enable others to make and use my invention, I will describe its construction and operation.

I provide the counter-shaft *S* with a bevel-wheel, *B*, having two sets of teeth, *b* and *d*, and the crank-shaft *C* with two pinions *f* and *g*, which are hung loosely upon the shaft, the journal-box *h* being between them. The shafts *C* and *S* and the bevel-wheel and pinions are so arranged as to keep the wheels always in gear. I place the two clutches *j* and *k* upon the shaft *C*. They are feathered to the shaft in the usual manner. The clutches are operated by the forks *a* of the slide *s*, the latter being attached to the frame, and connected to the hand-lever *l*, as shown in fig. 2. When the lever stands in the position shown by the full lines, (fig. 2,) the fast speed is given to the crank-shaft and knife-bar, and when in the opposite position, shown by the dotted lines *l'*, they receive the slow speed. When it is placed at the intermediate point, the clutches are both thrown out of lock and the crank-shaft remains at rest. One clutch made double may be used by placing it between the pinions, and hanging the shaft by a box at the end or back of the pinions *f*. The two pinions may be rigidly attached to the crank-shaft, and two separate and independent bevel-wheels hung loosely upon the counter-shaft *S*, and the clutches *j* and *k* feathered to that shaft and made to lock to either of the bevels, the same as they now do to the pinions. The bevel-wheels should be both provided with long hubs or bearings upon the counter-shaft, if this construction is used.

What I claim as my invention, and desire to secure by Letters Patent, is—

The arrangement of the two loose pinions *f* and *g* on the crank-shaft *C*, in combination with the bevel-wheel having two sets of teeth *b* and *d*, when the said pinions are locked to the shaft by a clutch or clutches, substantially as herein shown and described and for the purposes set forth.

M. EASTERBROOK, JR.
